UNITED STATES PATENT OFFICE.

SECONDO GILETTI, OF EAST OAKLAND, CALIFORNIA.

BUILDING CONSTRUCTION.

1,022,841.

Specification of Letters Patent.

Patented Apr. 9, 1912.

Application filed March 25, 1911. Serial No. 616,844.

To all whom it may concern:

Be it known that I, SECONDO GILETTI, a citizen of the United States, residing at East Oakland, in the county of Alameda 5 and State of California, have invented new and useful Improvements in Building Construction, of which the following is a specification.

This invention relates to building construction and particularly to a method of producing hollow, smooth, finished-surfaced walls and partitions in sanitary, reinforced concrete buildings.

The object of the present invention is to 15 provide a device and method for the construction of smooth, finished-surfaced walls, partitions, ceilings and other structural elements in buildings; to provide means whereby a complete building may be erected in a 20 fully finished condition with the exception of the doors and windows; and to provide a method of producing a substantially fire-proof, monolithic structure at an expense much less than at present necessary by 25 making a matrix with a smooth finished interior, and afterward filling the chamber of the matrix and providing means for rendering the walls or structural elements air and water-proof.

It is also a purpose of the present invention to evolve a method in the construction of buildings whereby the use of expensive and labor requiring devices may be eliminated, and the erection of the building continued by the use of a simple pumping apparatus whereby the material of which the structure is to be composed is delivered into the chambers of the matrix; and also to provide a matrix for building construction 35 having a smooth interior surface, which matrix comprises a number of complementary, coöperative, removable sections adapted to be assembled in the process of erection and permit the completion of successive 40 stories of the building by regular stages.

The invention consists of the parts and the construction and combination of parts, as hereinafter more fully described and claimed, having reference to the accompanying drawings, in which—

Figure 1 is a perspective view of a portion of the apparatus. Fig. 2 is a transverse vertical section of a wall and the molding or

framing matrix. Fig. 3 is a horizontal sectional view of a removable support 15, showing an exterior shell.

In the present invention I have shown an embodiment comprising a number of wooden frames or sections, which may be substantially the height of the wall of a room and 55 which sections may be of such width as to make the same conveniently portable and movable by an individual. These wall sections, as 2, are erected vertically upon a foot mold board framing section, as 3, having 60 the contour or face 4 of appropriate cross-sectional outline; and upon the upper end of the wall framing sections 2, when the latter have been assembled edge to edge, there is placed a longitudinal cove forming 65 member 5 of suitable exterior, contour and length. After the several vertical wall or partition forming sections 2 have been assembled and the cove forming member 5 positioned, a plurality of ceiling forming 70 sections 6 are lifted into position and keyed 75 therein by means of a number of removable insert or spacer keys 7 adapted to be supported upon the upper horizontal plate 8 of the several vertical sections 2.

The several mold forming sections 2, 5 and 6 are provided upon their matrix forming surfaces with a suitable sheeting 9 which may be of metal or any other appropriate material, which material is permanently attached to its relative section, and when the several sections have been positioned, there is presented a continuous, smooth, finished 85 surface, against which may contact a suitable plastic, self-hardening material, as 10, 90 which forms the permanent walls or structural elements of the building being erected.

In order to form a complete matrix for the reception of the plastic filling 10, there is suitably spaced from the first section of 95 assembled mold forming sections another set or series of sections which may be of such contour as is requisite for the formation of the desired face of the wall; such, for instance, as is shown on the outer side of the 100 filling 10 in Fig. 2, which represents the outside surface of a wall of a building.

In practicing my method of construction, I assemble the several mold forming sections of the desired face or outline as are 105 requisite for the formation of any given

shape or section of a wall of a building, and the erection may be rapidly accomplished by erecting a complete story at a time as the building progresses; thus a 5 complete matrix is formed for the first story of a building, by erecting such necessary sections 2, 5 and 6 as go to form the interior finished wall of a given room; the necessary openings of this room being pro- 10 vided by correspondingly formed mold sections. The exterior of the first story of the building is provided for by the erection of vertical mold sections 11 of suitable width and height and when these several inner 15 and outer sections have been assembled there is formed between them a space of the width desired in the thickness of the given wall. When the outside wall is being molded, it is frequently desirable to protect the interior 20 thereof against the transmission of moisture and cold air from the outside of the building, and this is accomplished by erecting in the matrix chamber between the sections a plurality of core shells 13 of suitable length 25 and cross-sectional area and spaced from each other a suitable distance for the provision of binding webs, as 14, between the adjacent vertical cores 13. I have found, that a very practical, economical water- 30 proofing core shell can be provided by the use of tar paper or other suitable material of suitable thickness and this is particularly adaptable for this purpose, as there is a close adhesion between the tarred shell or 35 core 13 and the plastic material, as the latter is filled into the matrix chamber. Since these flexible, pliable core forming shells 13 have not inherent stiffness or rigidity sufficient to support the load of the filling ma- 40 terial 10 as the latter is turned into the matrix, the core shells 13 are reinforced or supported during the process of construction by removable supports 15, which may be made of wood or other appropriate ma- 45 terial and which are indented or corrugated on their exterior surfaces. These supporting devices are adapted to be removed from the hardened walls or partitions of the building as soon as the filling 10 has set suf- 50 ficiently. Suitable reinforcing steel rods 16 may be introduced throughout the matrix chamber during the erection of the sections, thereby reinforcing the completed hardened walls of the building. After the 55 plastic filling has solidified and hardened, the key or retaining member 7 is withdrawn from above the shelf 8 of the vertical sections 2, thus permitting the several ceiling sections 6 to be lowered and re- 60 moved from the upper portion of the assembled frames, after which the cove forming members 5 are withdrawn and then the several wall forming sections 2 may easily be dismantled.

65 The purpose of providing the several

matrix forming sections with a smooth sheet lining of appropriate material is to insure that the hardened structural members of the building such as walls and partitions, etc., will have a smooth, finished surface and re- 70 quire no further treatment or coating; these being sufficiently dressed or finished to present a fine appearance.

Having erected the sections to form a matrix in which may be molded the first story of the building and pumping or otherwise suitably discharging a plastic filling material into the chamber of the matrix, this is allowed to solidify and the several mold sections dismantled and re-assembled 75 on the floor above, after which the filling material is charged into the matrix to form the second story of the building and so on successively for as many floors as there are in the finished structure. 80

It will be seen that by this method and apparatus thin solid or hollow partitions between rooms may be molded and integrally connected with the heavier main walls of the building and the floors all cast in one 85 continuous monolithic piece with air spaces and damp - proofing materials inserted between the outside walls and partitions as necessary, during the erection of the building. 90

The sheeting which is applied to the several matrix forming sections presents a 95 smooth, continuous substantially seamless surface, against which the filling material rests as it is charged into the erected sectional matrix and when the plastic material 100 has become sufficiently solid, the several sections may be dismantled, as hereinbefore explained, leaving a smooth, finished surface requiring no finishing coats; and such ornaments as are desired may be obtained 105 at window and door openings by so designing a cross-sectional area or contour of the molding sections as to produce a finished cast as desired. 110

By this method of construction a fireproof and moisture-proof building can be erected at a cost not to exceed that of a frame building of similar design and size. The material of which the building is constructed can be readily pumped from the lower floors to the 115 floors in course of construction, thereby avoiding the use of hoisting machinery, wheel-barrows or other expensive apparatus for the placing of the plastic material in the matrix, and by this system very thin walls 120 can be constructed and the several demountable sections of which the mold is formed can be used repeatedly throughout the same building, thus greatly reducing the cost of the temporary work now required in the 125 erection of concrete structures.

As it is desirable to render the intersecting joints around the base-board and floor line rat and vermin - proof, I design the base mold section 3 with a curved nose and a de- 130

pending bead along its lower edge, as at 3^a, so as to mold a floor cove 3^b. The depression in the floor made by the bead 3^a is flushed up when the sections are removed.

5 One of the important features of this invention is the use and method or use of the tar paper or equivalent cores 13, and the means of supporting these cores against collapse by the use of removable, corrugated core supports 15. It is important that the flues which are thus formed in the walls after the core supports 15 are removed, should be waterproof and with the purpose and function of using tar paper or the like 10 as a sheathing to the walls of the flues thus formed in the concrete. These tar paper or equivalent tubes, when put in, are sealed so as to be watertight. The removable core supports 15, by making them with corrugated vertical edges, as shown, can be made 15 cheaply and in one piece, and a single core support will do for an entire story in a building. They are easily removed, because the narrow lines of contact between the 20 apices of the support and the paper confer a minimum degree of hold on the paper, as 25

compared with the cementitious bond between the paper and core.

Having thus described my invention, what I claim and desire to secure by Letters Patent is—

An improved building construction, comprising vertical wall-forming frame sections and means for holding them in position, vertical core shells positioned between the wall-forming sections, said core shells being formed of tar-paper or like water-proof material having little inherent rigidity, and core supports removably fitting within the core shells and adapted to support the walls 35 of the same against the pressure of the filling material when introduced around the core shells, said core-supports having corrugations, the apices of which form narrow 40 lines of contact with the core-shells. 45

In testimony whereof I have hereunto set my hand in the presence of two subscribing witnesses.

SECONDO GILETTI.
